RUFFLER

Herbert H. Russell, New Haven, Conn., assignor to
The Greist Manufacturing Company, New
Haven, Conn., a corporation of Connecticut

Application June 27, 1952, Serial No. 295,909

1 Claim. (Cl. 112—135)

1

This invention relates to sewing machine attachments and more particularly to an attachment for making ruffles or gathers which can be attached to the usual household sewing machine.

In devices of this kind it is usual to provide a frame adapted to be attached to the presser bar of the sewing machine upon removal of the usual presser foot, and this is true of the present attachment. Upon this frame is pivoted a pendulum lever which is connected at its lower end to a carrier member to which the ruffling blade is attached. The pendulum lever is oscillated by the oscillations of a fork arm pivotally carried by the frame, which fork arm is bifurcated at one end to embrace the needle screw of the needle bar of the sewing machine to which the device is attached so that upon reciprocation of the needle bar gathers or ruffles will be made in the material and stitches will be effected through these gathers or ruffles.

Also means are usually provided for varying the spacing apart of the ruffles or gathers so as to vary the number of sewing machine stitches between adjacent ruffles, and also means are provided to adjust the travel of the ruffling blade to make coarse or fine ruffles in the material.

It is with this latter adjusting mechanism that the present invention is particularly concerned in that novel mechanism is provided to adjust the throw or stroke of the pendulum lever and the ruffling blade which is attached thereto.

In devices of this character, it is not only desirable to provide adjustments so that a wide variety of work may be performed with the attachment, but it is also desirable that these adjustments be conveniently made and be simple in character so that the attachment may be used by the ordinary person not especially skilled in the art of sewing.

In the present instance the mechanism for adjusting the throw or stroke of the ruffling blade comprises a screw which is threadedly connected to the pendulum lever so that by turning the screw in one direction or the other the adjustment may be made. In addition a simple and effective locking means is provided for releasably holding the screw in any position to which it has been adjusted, the holding being effected automatically without any attention on the part of the operator and without interfering with subsequent adjustment when such is desired.

One object of the invention is to provide a new and improved sewing machine attachment for making ruffles or gathers.

2

A further object of the invention is to provide a new and improved sewing machine attachment having novel mechanism for adjusting the throw or stroke of the ruffling blade so as to vary the width of the gathers or ruffles.

Still another object of the invention is to provide convenient and simple means for adjusting the throw of the ruffling blade and means for frictionally holding the adjusting mechanism in any desired adjusted position.

To these and other ends the invention consists in the novel features and combinations of parts to be hereinafter described and claimed.

In the accompanying drawings:

Fig. 1 is a side elevational view of a ruffler attachment embodying my improvements;

Fig. 2 is a similar view taken from the other side of the attachment;

Fig. 3 is a view of the pendulum lever with the adjusting screws and holding device mounted thereon;

Fig. 4 is a sectional view on line 4—4 of Fig. 3; and

Fig. 5 is a detail perspective view of the locking or holding device for the adjusting screw.

To illustrate a preferred embodiment of my invention I have shown in the drawings a ruffler attachment comprising a frame 10 to which may be secured an adapter 11, which adapter is adapted to be attached to the presser bar of the sewing machine in order to secure the attachment thereto.

Pivoted mounted at 12 on the frame 10 is the usual fork arm 13 having a bifurcated front end 14 adapted to be connected to the presser bar of the sewing machine in the usual manner.

Also pivoted upon the pivot 12 is a pendulum lever 15, this lever having at its upper end a shoulder 16 adapted to be engaged by a pawl 17 carried by a pawl carrier 18 adjustably mounted on the fork arm 13.

It will be apparent that as the fork arm is reciprocated the pawl 17 will strike the shoulder 16 and move the pendulum lever in one direction which will be a clockwise direction about the pivot 12, as shown in Fig. 1. Means such as a ratchet wheel 19 having shallow and deep teeth therein may be provided to be engaged by the pawl 17 and prevent this pawl from engaging the shoulder 16 except at certain times (when the deep teeth are engaged by the pawl) so as to vary the spacing of the ruffles. This particular mechanism is old in the art and needs no further description.

To the lower end of the pendulum lever 15 is

pivoted a carrier 20 for the ruffling blade 21, and cooperating mechanism designated generally by the numeral 22 is provided to cooperate with the blade and form ruffles in the material as the sewing machine is operated.

There has been described above the means for operating the pendulum lever in one direction. It is also necessary, of course, to move this lever in the opposite direction or in a counter-clockwise direction, as shown in Fig. 1, in order to restore it to its original position after an operative stroke. For this purpose a finger or kicker 23 is provided upon the fork arm 13, this member being adapted to engage the end of a screw 24 threaded through an ear 25, the ear being formed integrally with the pendulum lever 15 and extending laterally with respect thereto. It is provided with a threaded opening to receive the screw so that the latter is adjustable with respect to the lever so as to vary the position of the end of the screw with respect to the finger 23.

It will be seen that this provides a ready and convenient means for adjusting the throw of the pendulum lever, and, therefore, the throw of the ruffling blade. As the screw 24 is backed off so that it moves toward the right as shown in Fig. 1, the finger 23 will only engage this lever toward the end of the downward stroke of the fork arm 13 so that a relatively small throw or stroke will be imparted to the lever 15. Adjustment of the screw in the other direction will, of course, increase the stroke.

In order to releasably and frictionally hold the screw in any position to which it may be adjusted and at the same time permit it to be freely adjusted in either direction when desired, a holding member is provided, as shown in Fig. 5. This member comprises a flat base portion 27 which may be provided with an opening 28 through which passes a rivet or the like 29 to secure the member to the pendulum lever. The holding member also includes a curved or partially cylindrical portion 30 designed to embrace the screw, as shown in Figs. 3 and 4. This portion 30 of the holding member is provided with screw threads 31, and the member is of spring material so that by its inherent resiliency it will grip the screw over a considerable area and hold it against

accidental rotation or adjustment while at the same time the threads will permit the screw to be readily adjusted by rotation. It will be seen, therefore, that while the holding member serves its purpose efficiently, it does not have to be moved or detached in order to permit adjustment of the screw but rather performs its holding function automatically after each adjustment of the screw. The portion 27 of the holding member may be provided with a spur 32 which is received in an opening 33 in the pendulum lever to secure the holding member firmly in position.

While I have shown and described a preferred embodiment of my invention, it will be understood that it is not to be limited to all of the details shown, but is capable of modification and variation within the spirit of the invention and within the scope of the claim.

What I claim is:

A ruffler attachment for sewing machines comprising a frame, a fork arm pivoted thereon, a pendulum lever pivoted to the frame, means connecting said fork arm to the lever to move the latter in opposite directions upon oscillation of the fork arm, the means for moving the lever in one direction comprising a projecting finger on the fork arm, a screw threadedly mounted on the lever in position to be engaged by said finger, said lever having thereon a laterally projecting ear provided with a threaded opening, said screw being threaded in said opening for adjustment relatively to the lever, a spring member having a flat portion secured to the lever and a curved portion to snugly embrace the screw to hold the latter in adjusted positions and the flat portion of the spring having a spur entering an opening in the lever to assist in securing the spring in place.
